UNITED STATES PATENT OFFICE.

FREDERICK S. YOUNG, OF PORTAGEVILLE, MISSOURI.

POTATO-CUTTER.

1,368,090.

Specification of Letters Patent.

Patented Feb. 8, 1921.

Application filed January 23, 1920. Serial No. 353,539.

To all whom it may concern:

Be it known that I, FREDERICK S. YOUNG, a citizen of the United States, residing at Portageville, in the county of New Madrid 5 and State of Missouri, have invented new and useful Improvements in Potato-Cutters, of which the following is a specification.

This invention relates to means for cutting seed potatoes into pieces containing one 10 or more eyes and the principal object of the invention is to provide means for cutting the potato into the desired number of pieces in one operation.

The invention can also be used for cutting 15 apples or other fruit into two or more pieces.

Another object of the invention is to provide a vertically arranged knife and horizontally arranged knives with means for detachably connecting said knives to the device 20 so that the desired knives may be removed for cutting the potatoes into a smaller number of pieces.

Still another object of the invention is to provide a manually operated slideable member 25 for pushing the potatoes against the knives and foot operated means for adjusting the potatoes relative to the sliding member so that potatoes of various sizes may be cut.

This invention also consists in certain 30 other features of construction and in the combination and arrangement of the several parts, to be hereinafter fully described, illustrated in the accompanying drawings 35 and specifically pointed out in the appended claims.

In describing my invention in detail, reference will be had to the accompanying drawings wherein like characters denote like 40 or corresponding parts throughout the several views, and in which:

Figure 1 is a side view of the apparatus.

Fig. 2 is a plan view.

Fig. 3 is a longitudinal section.

Fig. 4 is a cross section.

Fig. 5 is a detail view of the sliding member.

Figs. 6 and 7 are detail views of the knives and the manner of connecting them together.

In these views 1 indicates a table which 50 includes the legs 2, the side pieces 3 and the braces 4. An inclined chute 5 is carried by the table adjacent each end thereof and these chutes extend in opposite directions as 55 shown. A vertically movable platform 6 is

located between the side bars of the table with its ends extending over the upper ends of the chutes. This platform is carried by a downwardly depending arm 7 which passes through an opening 8 in one of the 60 cross braces of the central pair of legs and the lower end of this arm is pivotally connected to an upwardly extending bar 9 which is hinged at its lower end to a foot pedal 10 which is pivotally mounted at its 65 ends to the lower ends of the central pair of legs. Thus by actuating said pedal with the foot the platform will be moved vertically. The platform is provided with a centrally arranged slot 11 to receive a vertically ex- 70 tends knife 12. This knife has its lower end bent at right angles and bolted to the cross piece through which the arm 7 ex- 75 tends. This knife is provided with a cutting edge at each side thereof and it is also provided with spaced notches 12' in each cutting edge. I also provide a pair of trans- 80 versely extending knives 13 which extend across the upper part of the table and have their ends bolted to the side bars thereof. These knives are spaced apart by the blocks 14 through which the bolts which connect the knives with the side bars extend. These knives 13 are provided with centrally ar- 85 ranged openings 15 and slits 15' which are formed in the walls of the openings. These slits are adapted to receive the edges of the vertically extending knife, and after the laterally extending knives reach the slots in 90 said vertical knife the said laterally extending knives are turned to place them at right angles to said vertical knife, the walls of the opening of each lateral knife engaging the slots in the vertical knife to permit this turning movement.

The side bars of the table are provided with guideways 16 and the pusher or sliding member 17 is slidably mounted on said side bars and has parts engaging said guideways. This member is formed with the large open- 100 ing 18 and with the upper and lower horizontal slots 19 which extend from one end to a point an appreciable distance from the other end. A vertical slot 20 is also formed in one end of the member, said slot com- 105 municating with the opening 18 and also with the horizontal slots. The side end of the member is formed with the handle 21 and with the guard 22.

The potatoes to be cut are placed one at a 110

time upon the platform between the knives and the end of the sliding member. The platform is then adjusted by means of the foot pedal to properly position the potato with respect to the knives and then the sliding member is moved forwardly to force the potato against the knives. It will be understood that the laterally extending knives will engage the upper and lower horizontal slots in said member while the central knife will pass through the vertical slot. The member is moved far enough to force the potato beyond the knives and off the end of the platform so that the pieces of potato will fall down the chute into a suitable receptacle.

Another potato is then placed on the opposite side of the knives and the sliding member moved in an opposite direction so as to bring the inner wall thereof against the potato and force the potato against the knives, it being understood that when the sliding member reaches the end of its first movement the knives will lie within the opening in said member and the potato is placed within said opening between the knives and the end wall of said opening which on the return movement of the sliding member it is moved far enough to force the pieces of potato off the end of the platform into the said chute. It will thus be seen that a potato is cut on each movement of the sliding member.

When desired one or more of the knives may be removed so as to cut the potatoes or other articles into a less number of pieces.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a table, vertically and horizontally arranged knives supported by said table, a sliding member having slots therein for receiving said knives for pressing the articles to be cut against the knives and a vertically

movable platform for supporting the articles to be cut, said platform being located below the sliding member.

2. A device of the class described comprising a table, vertically and horizontally arranged knives supported by said table, a 55 sliding member having slots therein for receiving said knives for pressing the articles to be cut against the knives and means for adjusting the position of the potatoes on the table in relation to the knives, said means 60 consisting of a vertically movable platform, a foot pedal and means for connecting the pedal to said platform.

3. A device of the class described comprising a table, a vertically movable platform thereon, chutes supported by said table with their upper ends adjacent the ends of the platform, a foot pedal connected with the platform, a vertical knife supported by the table, horizontally arranged knives associated with the vertical knife and a sliding member on the table having vertical and horizontal slots therein for receiving the knives for forcing the potatoes against said knives.

4. A device of the class described comprising a table, a vertical two-edge knife supported thereby, horizontally arranged two-edged knives supported by the table and associated with the vertical knife, a member 80 slidably mounted on the table and having a central opening and horizontal and vertical slots communicating with the opening and adapted to receive the knives for forcing the articles to be cut against said knives.

5. A device of the class described comprising a table, a vertically arranged two-edged knife thereon, said knife having spaced notches in its edges, horizontally arranged two-edged knives supported by the 90 table and having openings therein, the walls of which engage the notches in the vertical knife for holding said knives together and 95 slidably means for forcing the article to be cut against said knives.

In testimony whereof I affix my signature.

FREDERICK S. YOUNG.
